UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

SCRAPER.

Application filed October 25, 1927. Serial No. 228,871.

This invention relates to scrapers and more particularly to a Fresno bucket construction arranged to be drawn by a tractor.

An important object of the invention is 5 to provide a device of this character so constructed that it may be controlled in all of its movements by an operator directing the movements of the tractor and in such fashion that his attention is not distracted from 10 the control of the tractor.

A further object of the invention is the provision of a device of this character so constructed that the necessity of manipulating the tractor other than in straight ahead 15 travel to cause any of the operations of the bucket is eliminated.

A further and more specific object of the invention is to provide a construction of this character wherein the only actual connections 20 between the bucket and the tractor are pivotal connections about which the bucket may rotate.

A still further object of the invention is to provide a construction of this character 25 wherein the angular position of the bucket may be readily controlled, as regards both its loading and distributing positions, so that in the first instance, compensation may be had for varying degrees of hardness of 30 the soil acted upon and in the second instance, control may be had of the depth of the layer in which the soil is distributed.

A still further object of the invention is to provide a construction of this character, 35 wherein the latching mechanism employed is disposed at the longitudinal center of the bucket, so that a single latch will suffice and there is no tendency of the bucket to slew, as in the case where latches at opposite sides 40 of the bucket are provided and one of these latches disengages prior to the disengagement of the other.

These and other objects I attain by the construction shown in the accompanying 45 drawings, wherein for the purpose of illustration is shown a preferred embodiment of my invention and wherein:—

Figure 1 is a plan view of a scraper constructed in accordance with my invention, 50 portions being broken away;

Figure 2 is a side elevation of the scraper;

Figure 3 is a central longitudinal sectional view therethrough, the scraper being shown in dotted lines in the distributing position and in solid lines in the position

which it occupies when returning for a load;

Figure 4 is a longitudinal sectional view showing the distributing stop in engagement with the controlling latch element and 60 illustrating the adjustability of this stop;

Figure 5 is a plan view of the distributing stop removed.

Referring now more particularly to the drawings, the numeral 10 generally designates a bucket construction including a plate having a forward cutting edge 11 and an upturned rear portion 12. End walls 13 are secured to the plate and provided upon their outer faces adjacent the upper portions thereof is a trunnion 14. To the inner face of each side wall is secured a runner support 15, which is preferably in the form of an angle bar, the intermediate portion of which is arcuately curved and the end portions of which, indicated at 16, are inwardly directed and at substantially right angles to one another. These end portions are secured to the end walls 13, as indicated at 7, 75 17. Each runner support 15 has secured thereto a runner shoe 18 which is preferably bolted to the runner support to render the same readily removable and the upper ends of the runner shoes terminate substantially in vertical alignment with the trunnions 14. 80 85

Rearwardly of the upper ends of the runner shoes, the supports 15 are connected by a transversely extending bar 19, at the longitudinal center of which a latch element, generally designated at 20, is secured. This 90 latch element is arcuately curved, having substantially the same curvature as the runner shoe and is attached to the bar 19 adjacent its forward or upper end and to the back of the bucket at the center thereof and 95 adjacent its rear or lower end through a casting 21. The forward end of the latch element 20 is inturned to form a stop 22, while the rear end thereof is out-turned to form a second stop 23. Adjustably secured to the latch element intermediate the ends thereof is a casting 24 including a transversely extending portion 25 forming a third stop.

A draw bar is provided including bucket 105 engaging members 26, the rear ends 27 of which are parallel and connected at their rear terminals to the trunnions 14 and the forward ends 28 of which converge upon and are secured to parallel members 29, the for- 110

ward ends of which are adapted at 30 for connection with the tractor. The forward ends of the rearward portions 27 of the side members 26 are connected by a transversely 5 extending bar 31 to which the rear ends of the parallel members 29 are secured.

Secured to the parallel members, preferably by the securing elements 32 connecting the bucket engaging members 26 thereto is a 10 quadrant 33 for coaction with a lever 34, the lower end of which is pivoted between the parallel members 29. This lever has latch mechanism, generally designated at 35, whereby it may be held in adjusted positions 15 with relation to the quadrant and has connected thereto the forward end of a link 36. The link 36 is composed of two members, the rear ends of which are spaced and receive therebetween a latch element 37 having a 20 downwardly projecting nose 38.

Secured to the parallel members adjacent the rear ends thereof are the lower ends of a pair of supports 39 between the upper ends of which a bent lever, generally designated 25 at 40, is pivoted. Adjacent these supports, the link 36 extends and the supports are connected by a transverse element 41 serving as a limit for downward movement of the link. One arm of this bent lever, indicated at 42, 30 extends vertically and has connected to the upper end thereof an operating element 43 preferably in the form of a flexible cable, the opposite end of which extends to the tractor and is preferably attached thereto at some 35 point convenient to the hand of the operator. The second arm 44 of the lever extends rearwardly and is linked at its extremity to the link 36 by a link 45.

In the use of the apparatus, the nose 38, 40 when engaged with the stop 22, positions the bucket for filling and the angle at which the cutting edge 11 is presented to the ground, may be adjusted by manipulation of the lever 34. As this lever is moved forwardly, 45 the angle of the blade to the ground increases and as it is moved rearwardly, it decreases. To assist in the adjustment, the connection of the link 36 with the lever is adjusted preferably longitudinally of the 50 lever, as generally designated at 46. The bucket drawn over the ground at the proper angle thereto when it arrives at the dumping position is released by a pull upon the operating member 43, by means of which, 55 through the arm 44, the rear end of the link 36 is elevated to disengage the nose 38 and stop 22. When the release is effected, the operating element is released, permitting the 60 nose to come in contact with the latch element 20 upon which it rides until the rotation of the bucket brings the stop 25 into engagement therewith. At this time, the bucket rests upon the shoes 18 and is so positioned that its blade 11 acts as a leveler, 65 distributing the load contained in the bucket

in a smooth even layer over the ground. Distribution having been completed, a second switch upon the operating element 43 releases the nose 38 from the stop 25 and positions the nose for engagement with the 70 stop 23. When this stop comes into engagement with the nose, the bucket is held in such position that it moves upon the runner shoes 18 and is held with its blade 11 well spaced from the ground, so that there is no 75 danger of contact therewith of stones or other upstanding obstructions which would be liable to damage the same. Arriving at the place from which the load is being taken, a third twitch upon the operating member 43 80 releases the nose 38 from the stop 23, permitting the bucket to roll until the nose 38 again engages with the stop 22.

It is pointed out that by the construction employed, the angle at which the blade is 85 presented to the ground is made very readily adjustable and, at the same time, an adjustment is provided, as regards the position of the bucket when dumping, which may be adjusted to vary the layer provided without regard to the change of position of the nose 38, which is effected by the lever 34.

Since the construction hereinbefore set forth is capable of a certain range of change and modification without materially departing from the spirit of the invention, I do not limit myself to such specific structure except as hereinafter claimed.

I claim:—

1. In a scraper, a draw bar, a transversely 100 extending scraper bucket rotatably engaged therewith and adapted to assume loading, dumping and transporting positions, a latch element supported from the draw bar and a coacting latch element carried by the bucket 105 and having stops successively engaged by the first named latch element to check rotation of the bucket in each of said positions and means operable at the forward end of the draw bar for disengaging the first named 110 latch element, a lever pivoted to the draw bar adjacent the forward end thereof to swing longitudinally of the draw bar, means for holding the lever in adjusted positions, the first named latch element comprising a 115 link pivoted at its forward end to the lever and having at its rear end a nose for engagement with said stops.

2. In a scraper, a draw bar, a transversely 120 extending scraper bucket rotatably engaged therewith and adapted to assume loading, dumping and transporting positions, a latch element supported from the draw bar and a coacting latch element carried by the bucket 125 and having stops successively engaged by the first named latch element to check rotation of the bucket in each of said positions and means operable at the forward end of the draw bar for disengaging the first named latch element, a lever pivoted to the draw 130

- bar adjacent the forward end thereof to swing longitudinally of the draw bar, means for holding the lever in adjusted positions, the first named latch element comprising a link pivoted at its forward end to the lever and having at its rear end a nose for engagement with said stops, the connection of the link with the lever being adjustable longitudinally of the lever.

3. In a scraper, a draw bar, a transversely extending scraper bucket rotatably engaged therewith and adapted to assume loading, dumping and transporting positions, a latch element supported from the draw bar and a coacting latch element carried by the bucket and having stops successively engaged by the first named latch element to check rotation of the bucket in each of said positions and means operable at the forward end of the draw bar for disengaging the first named latch element, a lever pivoted to the draw bar adjacent the forward end thereof to swing longitudinally of the draw bar, means for holding the lever in adjusted positions, the first named latch element comprising a link pivoted at its forward end to the lever and having at its rear end a nose for engagement with said stops, the stop controlling the bucket in its dumping position being adjustable longitudinally of the last named latch element.

4. In a scraper, a draw bar, a transversely extending scraper bucket rotatably engaged therewith and adapted to assume loading, dumping and transporting positions, a latch element supported from the draw bar and a coacting latch element carried by the bucket and having stops successively engaged by the first named latch element to check rotation of the bucket in each of said positions, the first named latch element comprising a link having a pivotal connection at its forward end with the draw bar adjacent the forward end thereof, a pair of spaced supports arising from the draw bar adjacent the rear end thereof and adjacent which said link extends, a connection between the supports limiting downward movement of the link and a pivoted bent lever carried by the upper ends of said supports and having an arm extending rearwardly over the link and linked thereto and an operating element secured to the upper end of the other arm of the lever and extending forwardly therefrom, the pivotal connection between the link and the forward end of the draw bar comprising a pivoted lever swingable longitudinally of the draw bar and to which the link is pivoted and means associated with the link for securing the lever in adjusted positions.

5. In a scraper, a draw bar, a transversely extending scraper bucket rotatably engaged therewith and adapted to assume loading, dumping and transporting positions, a latch element supported from the draw bar and a coacting latch element carried by the bucket and having stops successively engaged by the first named latch element to check rotation of the bucket in each of said positions, the first named latch element comprising a link having a pivotal connection at its forward end with the draw bar adjacent the forward end thereof, a pair of spaced supports arising from the draw bar adjacent the rear end thereof and adjacent which said link extends, a connection between the supports limiting downward movement of the link and a pivoted bent lever carried by the upper ends of said supports and having an arm extending rearwardly over the link and linked thereto and an operating element secured to the upper end of the other arm of the lever and extending forwardly therefrom, the pivotal connection between the link and the forward end of the draw bar comprising a pivoted lever swingable longitudinally of the draw bar and to which the link is pivoted, means associated with the lever for securing the lever in adjusted positions, the pivotal connection of the link with the lever being adjustable longitudinally of the lever.

6. In a scraper, a draw bar, a transversely extending scraper bucket rotatably engaged therewith and adapted to assume loading, dumping and transporting positions, a latch element supported from the draw bar and a coacting latch element carried by the bucket and having stops successively engaged by the first named latch element to check rotation of the bucket in each of said positions, the first named latch element comprising a link having a pivotal connection at its forward end with the draw bar adjacent the forward end thereof, a pair of spaced supports arising from the draw bar adjacent the rear end thereof and adjacent which said link extends, a connection between the supports limiting downward movement of the link and a pivoted bent lever carried by the upper ends of said supports and having an arm extending rearwardly over the link and linked thereto and an operating element secured to the upper end of the other arm of the lever and extending forwardly therefrom, the pivotal connection between the link and the forward end of the draw bar comprising a pivoted lever swingable longitudinally of the draw bar and to which the link is pivoted, means associated with the lever for securing the lever in adjusted positions, the pivotal connection of the link with the lever being adjustable longitudinally of the lever.

7. In a scraper bucket, a draw bar, a bucket rotatably connected therewith and having runner shoes by which it is supported during a portion of the rotation, supports for said runner shoes, a bar connecting the supports, an arcuately curved latch element secured centrally to said bar adjacent its upper forward end and centrally to the back of the bucket adjacent its lower rear end, the ends of the bar having radial terminal portions forming stops, a third stop secured to the latch element intermediate the ends thereof and adjustable longitudinally thereof, a link pivoted at its forward end adjacent the

forward end of the draw bar and having its rear end extending over the bucket and provided with a nose for engagement with said stops and a lever operable from the 5 forward end of the draw bar for elevating the rear end of the link to disengage the nose from an engaged stop.

8. In a scraper bucket, a draw bar, a bucket rotatably connected therewith and having 10 runner shoes by which it is supported during a portion of the rotation, supports for said runner shoes, a bar connecting the supports, an arcuately curved latch element secured centrally to said bar adjacent its upper 15 forward end and centrally to the back of the bucket adjacent its lower rear end, the ends of the bar having radial terminal portions forming stops, a third stop secured to the latch element intermediate the ends thereof 20 and adjustable longitudinally thereof, a link pivoted at its forward end adjacent the forward end of the draw bar and having its rear end extending over the bucket and provided with a nose for engagement with said 25 stops, a lever operable from the forward end of the draw bar for elevating the rear end of the link to disengage the nose from an engaged stop, the pivotal connection between the link and the forward end of the 30 draw bar comprising a lever pivoted to the draw bar to swing longitudinally thereof and

to which the forward end of the link is pivoted and means for latching said bar in an adjusted position.

9. In a scraper bucket, a draw bar, a 35 bucket rotatably connected therewith and having runner shoes by which it is supported during a portion of the rotation, supports for said runner shoes, a bar connecting the supports, an arcuately curved latch element 40 secured centrally to said bar adjacent its upper forward end and centrally to the back of the bucket adjacent its lower rear end, the ends of the bar having radial terminal portions forming stops, a third stop secured to the latch element intermediate the ends thereof 45 and adjustable longitudinally thereof, a link pivoted at its forward end adjacent the forward end of the draw bar and having its rear end extending over the bucket 50 and provided with a nose for engagement with said stops, a lever operable from the forward end of the draw bar for elevating the rear end of the link to disengage the nose from an engaged stop, supports for 55 said lever extending upwardly from the draw bar and with which the link is engaged for guidance and means connecting said supports limiting downward movement 60 of the rear end of the link.

In testimony whereof I affix my signature.
FRANKLIN E. ARNDT.
